CLAIM

The ornamental design for a combined knife, fork and spoon set, as shown.

DESCRIPTION

FIG. 1 is a front elevational view of a combined knife, fork and spoon set showing our new design;
FIG. 2 is a rear elevational view thereof;
FIG. 3 is a top plan view thereof;
FIG. 4 is a bottom plan view thereof;
FIG. 5 is a left end elevational view thereof;
FIG. 6 is a right end elevational view thereof;
FIG. 7 is a cross-sectional view taken along line 7—7 of FIG. 3;
FIG. 8 is a cross-sectional view taken along line 8—8 of FIG. 1;
FIG. 9 is an exploded top perspective view thereof; and
FIG. 10 is an exploded bottom perspective view thereof.
